(57) **CLAIM**

The ornamental design for the hair straightener apparatus, as shown and described.

DESCRIPTION

FIG. 1 is a perspective view of the hair straightener apparatus in accordance with the principles of the present disclosure; FIG. 2 is a left side elevation view of the hair straightener apparatus; FIG. 3 is a right side elevation view of the hair straightener apparatus; FIG. 4 is a front elevation view of the hair straightener apparatus; FIG. 5 is a top plan view of the hair straightener apparatus; and, FIG. 6 is a bottom plan view of the hair straightener apparatus. The broken lines shown in the drawings illustrate a portion of the hair straightener apparatus and form no part of the claimed design.

1 Claim, 4 Drawing Sheets
